UNITED STATES PATENT OFFICE.

JAMES LEONARD PLIMPTON, OF BOSTON, MASSACHUSETTS.

ROLLER-SKATE.

No. 906,281.

Specification of Letters Patent.

Patented Dec. 8, 1908.

Application filed December 24, 1907. Serial No. 407,893.

To all whom it may concern:

Be it known that I, JAMES LEONARD PLIMPTON, a citizen of the United States, and a resident of Boston, in the county of Suffolk and State of Massachusetts, have invented a new and Improved Roller-Skate, of which the following is a full, clear, and exact description.

This invention relates to and is dependent upon the construction, arrangement and mode of operation of that class of guidable curved-running roller skates as originated and first patented by me in the United States, January 6, 1863, and more particularly as improved and patented by me in England, August 25, 1865, and in the United States June 26, 1866. In this class of guidable curved-running roller skates the rollers are applied to the stock or foot-stand of the skate so that the said rollers may be cramped or turned, so as to cause the skate to run in curved lines either to the right or left by the turning, canting or tilting laterally of the stock or foot-stand.

To enable others skilled in the art to understand and carry my improvement into use, I preferably employ, illustrate and describe, transporting, guiding and adjusting parts of the best and most extensively used modification of guidable roller skate as set forth in the patents above referred to, but do not confine the applying of my late improvements for better control to this one particular construction of guidable roller skates, as many variations therefrom or many well constructed guidable roller skates may be substituted without deviating from the purpose or object of my new and improved skate, the object and purpose of which is to give the skater additional and better control over guidable roller skates of the class described. A leading control of my new skate is in providing certain further original construction, arrangement and adjustment of parts, which when properly constructed, applied, and combined with parts of guidable roller skates of the class described, will enable the skater at will, to shorten, retard, or bring to a stop, any large or small curved glides that the skate may be making, however much or little the foot-stock or guiding portion upon which the foot stands may be canted laterally in either direction, without raising any of the rollers from the surface skated upon.

Certain other means are added and com-

bined in the new skate for giving more comfortable and uniform control for guiding with other means and adjustments to favor the beginner or timid skater, by changing the level of the foot, and for changing the size and direction of the curved glides and the readjustment of the same as proficiency increases.

Reference is to be had to the accompanying drawings, forming a part of this specification, in which similar characters of reference indicate corresponding parts in all the figures, and in which

Figure 1 is a side elevation of a skate embodying one simple and practical form of my invention; Fig. 2 is an inverted plan view thereof; Fig. 3 is a vertical longitudinal section through the rear portion of the skate, said section being taken on the line 3—3 of Fig. 2; Fig. 4 is an inverted plan view of one of the two members forming the foot-stock or stand, and the supporting plate for the rear rollers; Fig. 5 is a view of the rear end of the skate; Fig. 6 is an end view showing means for adjusting the position of the heel in respect to the foot-stock; Fig. 7 is an end view showing the adjusting means shown in Fig. 6 and employed for supporting worn heels; Figs. 8, 9 and 10 are perspective views, showing modified forms of brake shoes; Fig. 11 is an inverted plan view of the supporting plate for the front rollers, showing means for additionally adjusting it; and Fig. 12 is a vertical section on the line 12—12 of Fig. 11, showing in solid lines the plate adjusted for large curves, and showing in dotted lines the plate adjusted for small curves.

In the new and improved skate illustrated in the accompanying drawings, I employ a foot-stock or stand having means for securing same to the foot of a skater as shown, and having front and rear rollers so mounted that they may be moved out of parallelism to cause the skate to run in varying curved lines by the turning, canting, or tilting laterally of the foot-stock.

In the new skate the foot-stock or guiding portion upon which the foot stands to guide the skate, is formed of two separate members 10 and 11, resiliently supported in respect to each other, and one of these members 10, carries the front rollers and the means for attaching the skate to the foot, while the other member 11 carries the rear rollers and the greater portion of the means

for retarding, said means being operated by the relative movement of the two members. The weight, pressure or force employed for retarding the wheels is transferred or transmitted at or near a point of equal radial distance therefrom, having little or no motion in relation to the diagonal transverse rocking motion which will be found about in a line with the inclined axis, or diagonal transverse rocking motion upon which the guiding of this class of skates depends, and so that a given length of movement of such force will have nearly the same effect at whatever angle the foot-stock may be inclined laterally in making very large or very small curved glides. The member 10 is formed of wood or any other suitable material, and has substantially the same general contour as the sole of the shoe.

The shoe 12 of the skater is the pliable medium through which the movement of the skater's foot is transferred to the foot-stock for guiding the skate. The bottom of the shoe may be made or worn rounding, or one side worn more than the other; to prevent such a shoe from rocking or causing the foot to stand untruly while guiding the skate, suitably placed and oppositely located chambered threaded holes are made in the foot-stock, into which slotted, threaded circular-ridged bolts or screws 10^a are inserted, and the top of the enlarged ridged bolt head is preferably adjusted in the chambers level with the surface of the foot-stock, so that the side of the shoe least worn may stand closely upon the foot-stock, as shown in Fig. 7. The ridge adjusting bolt on the opposite side may be raised and adjusted, so that the worn side of the sole or heel may be raised or adjusted, thus standing the center of the skater's foot truly over the center of the foot-stock however one-sided the bottom of the shoe may be worn, and thereby preventing rocking or loss of motion. The bolts are also useful in adjusting the position of the heel in respect to the skate-stock, in case the shoe or foot itself is twisted, as shown in Fig. 6, the retaining straps for the foot being removed to facilitate illustration in this figure, as well as in Fig. 7. The shoe 12 is further assisted in true, uniform and pliable guidance by means of adjustable strips 15, jointed to the foot-stock so as to fold conveniently when not in use; when in use, they may be adjusted from the lower end so as to be raised from the foot-stock in a diagonal direction, so as to fit the shoe closely and cross one another at the small or narrow portion of the rounded back of the shoe at a point somewhat below the play of the ankle joint, and pass diagonally upward to or near the ankle joint, a short distance beyond which they are fastened by elastic or other suitable fastenings, as shown in Fig. 1. By means of these guiding strips, the ra-

dius of a curved glide may be shortened according to the additional assistance or leverage thereby given to the shoe while pliably guiding the skate. The shoe 12 rests upright on the member 10 of the foot-stock, and the latter carries a plurality of straps or bands 13 and 14, or any other suitable means for securing the skate to the shoe.

At the under side of the member 10 at the front end, there is provided a member 16, termed a plate, having a downwardly-extending ledge 17, disposed longitudinally of the skate and having its lower surface disposed at an angle of approximately forty-five degrees to the horizontal, which may be varied and which forms an important part for guiding this class of skates and for laterally adjusting the guiding axle in either direction. The plate 16 is illustrated in Figs. 1 and 2 as being secured directly to the foot-stock member 10, by suitable screws, but to facilitate the adjustment I preferably insert between it and the member 10, a sheet metal plate 16^a, shown in Figs. 11 and 12. This plate has a centrally disposed adjustable screw 16^b, forming a fulcrum for changing the degree of inclination of the inclined axis, and also the lateral adjustment of the guiding axle in either direction. By tightening and loosening the several screws 16^c, holding the plate to the foot-stock, said plate may be held rigid in the desired adjusted position. In engagement with the plate 16, there is provided a hanger 18, comprising a transverse bar 19 and four inclined dependent bars or arms 20, 20^a, 20^b and 20^c. The bar or transverse portion of the hanger is provided with a curved recess 21 in its upper surface, designed for the reception of the curved lower surface of the inclined ledge 17, and is provided with a journal 22, substantially in alignment with the ledge and fitting into a recess in the plate. The hanger is secured to the plate by means of an attaching and adjusting screw 23, extending upwardly at substantially right angles to the line of the inclined journal and ledge, and extending through an opening in the plate. Upon the upper end of the adjusting screw, is mounted a resilient member 24, comprising, preferably, a block of rubber. Two rollers 25, 25^a are provided between the two pairs of dependent arms or bars 20, 20^a, and 20^b, 20^c, both of the rollers being mounted on a common axle 26.

The second member 11 of the foot-stock or stand is directly connected to the member 10, above described, and is movable in respect thereto, said member 11 being of substantially the same general contour as the rear portion of the member 10. The two members are securely held together at the forward end of the lower member 11, which is at approximately the central portion of the upper member 10, by means of a suitable

screw 27, Fig. 2, for holding the flange 29 of the plate 11 in the slot cut across the foot-stock. Intermediate the ends of the lower member, it is secured to the upper member 5 by two oppositely-disposed screws 28. The forward end of the lower member is preferably turned up to form the flange 29, which spaces the members apart, while the central portion of the member is free to move to or 10 from the upper member along the securing screws. The rear end of the lower member is unattached to the upper member, but is spaced therefrom by a plurality of resilient means, preferably, in the form of soft rubber 15 blocks 30 carried by either of the members but herein shown as being held from lateral movement by screws extending upward from the lower member 11.

Rigidly secured to the under surface of 20 the member 11 of the foot-stock, there is provided a plate 31, having a downwardly-extending inclined ledge 32, corresponding to the ledge 17 on the front plate 16, and having a hanger 33 secured to the plate and 25 in engagement with said ledge. The rear end of the hanger is provided with an upwardly-extending flange 34, adapted to fit in a groove 35 in the plate 31, and it is also provided with a journal 36, extending 30 through an opening 37 in the plate. The ledge 32, the flange 34, and the journal 36 are all substantially in alinement, and are disposed in a general direction at approximately forty-five degrees to the horizontal. 35 The lower hanger is provided with downwardly-extending arms 37, 37^a, 37^b and 37^c, serving for the support of an axle 38, upon which are mounted the two rear rollers 39 and 39^a. The lower hanger is held in engagement with the plate by a suitable adjusting screw 40 extending upward through 40 a recess in the plate and carrying a resilient rubber block 41. With the hangers and plates of the skate constructed as illustrated, 45 the resilient blocks 24 and 41 normally tend to hold the front and rear axles 26 and 38 parallel and all of the rollers in parallelism, but as the foot-stock or stand is turned, canted or tilted to either side, the hangers 50 are moved in respect to the corresponding plates and the rollers are brought out of parallelism, to turn the skate and guide it in a curve corresponding to the direction and extent of the turning, canting or tilting 55 movement of the foot-stock.

The greater portion of the retarding mechanism is carried by the hanger of the rear rollers, and is so constructed as to be operated by a variation in the relative positions of the two members 10 and 11 of the foot-stock, and a compression of the resilient blocks 30 resulting from a variation in the distribution of the weight or pressure of the skater upon the foot-stock. The retarding 60 mechanism preferably comprises a metal 65

plate 42, having one end thereof rigidly secured to the hanger by a screw 43, and having the opposite end disposed adjacent the rear portion of the circumferential face of the rear rollers. The outer transverse end of 70 this plate constitutes a brake bar or plate, and is preferably provided with two brake shoes 44 in the form of metal clips, engaging with the opposite surfaces of the brake bar at its ends and designed to be readily 75 detached and replaced by new ones, in case they become materially worn, by simply drawing off the worn shoe and sliding on the new brake shoe of the desired thickness. In Fig. 9, I have shown one of the brake 80 shoes detached, while in Figs. 8 and 10, I have shown slightly modified forms 44^a and 44^b. For normally holding the brake shoes out of engagement with the rollers, I provide a block 45 loosely mounted on the axle 85 38, intermediate the arms 37^a and 37^b, and carrying two screw bolts 46 extending outwardly through the brake bar or plate. The brake plate is free to move longitudinally of these screw bolts, but normally forced outward and away from the rollers by coil springs surrounding the bolts. For forcing the brake into engagement with the rollers and in opposition to the action of these springs, I provide an operating lever in the 90 form of a plate 47, substantially triangular in form and having the base portion loosely mounted upon the screw bolts 46, and having the apex extending upward toward the foot-stock member 10. The plate is so formed that as the upper apex is moved outward, the base portion below the screw bolt is moved inward and forces inward the lower edge of the plate 42 carrying the brake shoes. The lower ends of the plate 47 are bent 95 inward and engage with the outer edges of the clips forming the brake-shoes and normally prevent the accidental displacement of the latter. Extending downwardly from the foot-stock member 10, adjacent the rear end 100 thereof, I provide a screw bolt 48, having a conical end normally in engagement with the inner surface of the apex of the plate 47. As the operating lever, or plate 47, and the tapered-head screw bolt 48 are carried by 105 separate members of the foot-stock, it is evident that upon the compression of the rubber blocks 30 and the bringing together of the rear ends of the two foot-stock members, the tapered end of the adjusting screw 110 115 will force outwardly the apex end of the operating lever, or plate 47, and force inwardly the lower end to apply the brake. When the rounded end of the lever bears against the ridge on the conical-headed screw, the lower 120 screws 46 formerly used as a fulcrum, will then act uniformly to bring direct pressure to bear on the brake shoes, according to the adjustment of the conical-headed adjusting screw and the weight or pressure applied. 125 130

Thus showing that the transfer of motion or pressure may be uniformly made in either of two ways at whatever angle the foot-stock may be inclined laterally in making very small or large curves.

All of the parts forming the retarding mechanism are so constructed that they may be adjusted to cause the application of the brakes when any desired pressure is applied to the rear or heel portion of the skate. The degree to which the resilient blocks 30 are normally compressed when no weight is applied to the skate, is readily controlled by tightening or loosening the screws 28. To cause the brakes to apply when the resilient blocks have been compressed to any desired extent, the conical-headed screw bolt 48 may be rotated to vary its normal position in regard to the operating lever 47. The normal distance of the brake shoes from the rollers may be controlled by loosening or tightening the screw bolts 46. For controlling the inclination of the upper surface of the plate 31 in respect to the foot-stock member 11, the two are preferably connected by a plurality of screws 49, two of which are disposed adjacent each end of said plate. Intermediate the two members 31 and 11 is preferably disposed a spacing member 50, the position of which may be adjusted to bring it closer to or farther from either of the sets of screws 49. The spacing member also serves as a pivot or fulcrum, whereby without changing its position, either pair of screws is loosened and the other pair tightened, so as to change the inclination of the inclined axis so as to vary the curved glides with a given turning, canting or tilting laterally of the foot-stock. The rear screws 49 preferably extend through the foot-stock member 11 a sufficient distance to normally retain the resilient blocks in place.

It is evident that the retarding mechanism may be applied so as to act on the retarding rollers of one or both skates, and various changes may be made in shape, size and arrangement of the adjusting, guiding and retarding parts without departing from the spirit or object of the invention, which is to furnish means to enable one or more skaters to skate in very small or large curves without applying any retardation and at any time be able to more or less shorten or retard any or all glides gracefully or to safely stop or stand at a predetermined point or position, and thus render possible a new order of concerted or time-measured figure skating within a much smaller space than heretofore possible.

Having thus described my invention, I claim as new and desire to secure by Letters Patent:

1. In a roller skate, a foot stock, a roller, means whereby the turning, canting or tilting laterally of the foot stock guides the

skate in curved lines, a brake adjacent said roller and adapted to engage therewith and having a permanent relationship thereto independent of said turning, canting or tilting of the foot stock, and means for applying said brake by a variation in the distribution of pressure lengthwise of the foot stock.

2. In a guidable roller skate, a foot stock, rollers, means for mounting the same whereby they may be moved out of parallelism, to cause the skate to run in varying curved lines by the turning, canting or tilting laterally of the foot stock, a brake movable with one of said rollers during said movement of the latter out of parallelism, and means for applying said brake to said roller by a variation in the distribution of pressure lengthwise of the foot stock and independent of said tilting movement.

3. In a roller skate, a foot stock or stand, a plurality of pairs of rollers, means for connecting each pair of rollers to said foot stock, each of said means including two members movable in respect to each other and along inclined axes, whereby the turning, canting or tilting laterally of the foot stock tends to guide the skate along curved lines, and means for universally adjusting the position of one of said members in respect to said foot stock, to vary the inclination of said axis.

4. In a roller skate, a foot-stock or stand, comprising two members, means for securing one of said members to the foot of a skater, a roller carried by the other of said members, a brake carried by the last-mentioned member, resilient means separating the members, and an operating lever for said brake and controlled by the relative positions of the two foot-stock members.

5. In a roller skate, a foot-stock or stand, a plurality of pairs of rollers, means for connecting each pair of rollers to said foot-stock, each of said means including two members movable in respect to each other along an inclined axis whereby the turning, canting or tilting laterally of the foot-stock operates to guide the skate along curved lines, and means for varying the inclination of said axes longitudinally of the skate and also laterally thereof.

6. In a roller skate, a foot-stock or stand, a plurality of pairs of rollers, means for connecting each pair of rollers to said foot-stock, each of said means including two members movable in respect to each other along an inclined axis, whereby the turning, canting or tilting laterally of the foot-stock operates to guide the skate along curved lines, a brake for one of said pairs of rollers, and means operating substantially in alignment with one of said axes for applying said brake upon a variation in the distribution of pressure on the foot-stock.

7. In a roller skate, a foot-stock, a plurality of rollers, means for mounting the same, whereby they may be moved out of parallelism to cause the skate to run in varying curved lines by the turning, canting or tilting laterally of the skate, and adjustable means carried by said foot-stock and adapted to engage with the shoe of a skater for varying the position of the foot-stock in respect to the under surface of said shoe.

8. In a roller skate, a foot stock, and means for securing said foot stock to the foot of the skater, said means including a flexible strap secured to said foot stock adjacent the heel thereof and adapted to cross

the ankle of the foot, and flexible strips, each having one end thereof secured to said foot stock intermediate the ends of the latter and extending rearwardly therefrom, said strips being secured together above the heel 20 of the foot and extending forwardly and connected together at the front of the ankle.

In testimony whereof I have signed my name to this specification in the presence of two subscribing witnesses.

JAMES LEONARD PLIMPTON.
